Oscar M. Clink, 1446 W. Slauson Ave.,
Los Angeles, Calif.

Filed Dec. 23, 1960, Ser. No. 63,379

Term of patent 14 years

(Cl. D31—4)

FIG. 1.

FIG. 2.

FIG. 3.

FIG. 1 is a side elevational view of a fishing rod handle embodying my new design, the opposite side being substantially the same and the bottom being substantially plain;

FIG. 2 is an enlarged transverse sectional view thereof taken on the line 2—2 of FIG. 1; and

FIG. 3 is an enlarged transverse sectional view thereof taken on the line 3—3 of FIG. 1;

The dominant features of my design reside in the portions shown in full lines.

The outer end of the handle, indicated at the lower end of FIG. 1, is closed, plain and flat.

I claim:

The ornamental design for a fishing rod handle, substantially as shown and described.
